TRAFFIC SIGNAL STANDARD

Filed Oct. 1, 1925

Inventor:
Cromwell A.B. Halvorson, Jr.
by *Howard S. Smith*
His Attorney.

UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

DESIGN FOR A TRAFFIC-SIGNAL STANDARD.

Application filed October 1, 1925. Serial No. 14,987. Term of patent 14 years.

To all whom it may concern:

Be it known that I, CROMWELL A. B. HALVORSON, Jr., a citizen of the United States, residing at Lynn, in the county of Essex, State of Massachusetts, have invented a new, original, and ornamental Design for Traffic-Signal Standard, of which the following is a specification, reference being had to the accompanying drawing, forming a part thereof.

The accompanying drawing is a perspective view of my new design.

I claim:

The ornamental design for a traffic signal standard as shown.

In witness whereof, I have hereunto set my hand this twenty-ninth day of September, 1925.

CROMWELL A. B. HALVORSON, Jr.
